(57) **CLAIM**

The ornamental design for an automatic cat feeder, as shown and described.

DESCRIPTION

FIG. 1 is a first perspective view of an automatic cat feeder showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The broken lines shown in the drawings depict portions of the automatic cat feeder that form no part of the claimed design.

The dot-dash lines in FIGS. 1 and 9 are used to indicate the area of the enlargement portion of the automatic cat feeder, and form no part of the design claim.
